UNITED STATES PATENT OFFICE.

TURE E. NORDBERG, OF NEW SWEDEN, MAINE.

SAFE.

1,260,700.

Specification of Letters Patent. Patented Mar. 26, 1918.

Application filed July 31, 1917. Serial No. 183,791.

To all whom it may concern:

Be it known that I, TURE E. NORDBERG, citizen of the United States, residing at New Sweden, in the county of Aroostook and 5 State of Maine, have invented certain new and useful Improvements in Safes, of which the following is a specification.

This invention relates to safes, and more particularly to a safe for receiving bottles 10 of milk, bread, newspapers, and similar articles so constructed as to permit ready insertion of articles while positively preventing removal of the same from the safe.

One of the main objects of the invention 15 is to provide a safe of simple construction and operation which may be produced at relatively small cost. A further object is to provide a safe having a plurality of compartments for receiving bottles of milk and 20 loaves of bread, or similar articles, means being provided for closing a compartment after an article has been placed therein. A further object is to provide simple and efficient means actuatable by an article placed 25 in a compartment for positively preventing opening of the doors of a particular compartment after an article has been placed in the same. Further objects will appear from the detailed description.

30 In the drawings:—

Figure 1 is a front view of a safe constructed in accordance with my invention.

Fig. 2 is a transverse vertical section taken through the safe.

35 Fig. 3 is a section taken substantially on line 3—3 of Fig. 2.

Fig. 4 is a section taken substantially on line 4—4 of Fig. 3.

Fig. 5 is a fragmentary underneath view 40 of the cover.

The safe is provided with a substantially rectangular or box-shaped body 1 having the end walls 2 and 3, bottom 4, and back 5. This body is constructed of sheet metal, and 45 is normally closed by a cover 6 hingedly secured to the bottom 4, as at 7. This cover fits snugly about the edges of the body and is provided, at its upper edge, with an integral flange 8 which projects across the 50 upper edge portion of the top of the safe, this flange being of increased width for substantially two-thirds of its length, as at 8a. The interior of the body of the safe is divided into three vertically extending compartments 9, 10 and 11 by the vertically disposed sheet metal partitions 12 and 13 se-

cured, at their lower ends, to the bottom 4 of the casing. The upper end of partition 13 is turned over to form a bead 14. Two spaced rods 15 and 16 are secured through 60 back 5 of the casing and through a horizontal sheet metal strip 17 positioned remote from the cover of the casing. The outer end of strip 17 is provided with an integral tab 18 which is secured through the 65 end wall 3 of the casing, the inner end of this strip being provided with a similar tab 19 secured through partition 13. Rod 15 forms a pintle which receives the sleeve 20 of a sheet metal door 21 which is thus 70 hingedly secured in the top of the casing, rod 16 providing a pintle for a similar door 22. Door 22 cooperates with a similar door 23 hingedly mounted on a rod 24 corresponding to rod 15 to close the compartment 75 10, the doors 22 and 23 being of such width as to overlap, as shown. Compartment 9 is closed by similar doors 25 and 26 mounted on the rods 27 and 28, respectively. The upper end of partition 13 is secured and 80 braced by the hinge sleeves of doors 21 and 22, the upper end of partition 12 being similarly secured and braced by the sleeves of doors 23 and 25. The compartment 11 is closed by doors 21 and 29 which are mounted 85 similarly to the doors above described. The doors are normally held in raised or closed position by means of springs 30 secured to the casing and to the partitions, these springs pressing against the under 90 faces of the doors so as to normally hold the same in raised position.

As will be noted from Fig. 3 of the drawings, the sheet metal strip 17 is mounted in spaced relation to the front edge of the body 95 of the casing, and partition 12 is narrower than partition 13. An inner cover or closure member 31 is mounted in the casing. This member is provided, at its outer edge, with an integral sleeve 32 which receives a rod 100 or pintle 33 secured in the bottom wall 4 of the casing and the end flange 34 at the top of the casing. The inner end portion of member 31 is turned out to provide an arm 35, the upper edge of which is turned 105 over to form an open bead 36 which fits snugly about the front edge of partition 13. When member 31 is in normal or closed position it forms a supplemental cover for compartments 9 and 10. When the outer 110 or main cover 6 is closed, member 31 cooperates therewith to form a compartment

37 for receiving newspapers and similar articles. To permit insertion of a newspaper into this compartment, the cover 6 is provided with an inwardly opening flap 38 5 hingedly secured thereto at one edge as at 39 and normally held in closed position by a wire spring 40 secured about the hinge pintle 41 and bearing against the inner face of the flap. As will be noted from Fig. 1, 10 the free edge of flap 38 is directed downwardly so that a properly folded paper inserted through cover 6 into compartment 37 will drop to the bottom of this compartment thus preventing removal of the paper. The 15 main cover 6 is normally secured in closed position by a suitable lock 42 secured on the inner face of the widened portion 8^a of flange 8, the bolt of which engages into a suitable sheet metal eye or loop 43 secured 20 through the strip 17. By this construction, when a folded newspaper or similar article has once been inserted into compartment 37, removal of the same by unauthorized persons is prevented.

25 The upper edge of the back 5 of the casing is turned over to provide an integral flange 44 extending the full length of the casing. This flange co-operates with the flange of cover 6 to positively prevent outward movement of the doors for closing the compartments 9, 10 and 11, these doors being of such width as to engage these flanges at their front and back edges. By depressing the pairs of doors for closing the compartments, an article may be readily inserted 30 into any one of the several compartments. It will be evident that, if means be provided for preventing inward movement of the doors after the insertion of an article into 35 one of the compartments, the removal of this article will be prevented.

40 The compartments 9 and 10 are intended more particularly for the reception of bottles of milk, compartment 11 being somewhat larger and intended for the reception of a loaf of bread. I have provided means actuatable by an article placed in any one of these three compartments for positively preventing inward movement of the doors for 45 closing the compartments. As the means employed is identical for all of the compartments, it is necessary to describe the means for but one compartment in detail. Referring more particularly to the means 50 for closing compartment 10—a sheet metal platform 45 is rockably mounted at the lower end of this compartment by means of a pintle rod 46 inserted through partitions 12 and 13 and through the peripheral flange 47 of the platform. This platform is normally held in raised position by a light tension coil spring 48 secured thereto at the front edge of the platform, the upper end of this spring being secured to back 55 of the casing, as at 49. A bell crank lever

50 is pivotally mounted on the back of the casing, at the center of compartment 10, by means of a pivot pin 51. A similar lever 52 is mounted in front of lever 50, these two levers being oppositely disposed. The horizontal arm 53 of lever 52 is loosely connected by a rod 54 to the flange 47 of platform 45, at the front thereof. Horizontal arm 55 of lever 50 is similarly connected by a rod 56 to flange 47, the rods 54 and 56 being equi-distant from the point of connection of spring 48 to the flange 47, this spring being secured at the center of the back edge of the flange. The levers 50 and 52 are so mounted as to have their upper arms moved into substantially vertical position when the platform 45 is depressed. The outer end of lever 50 is turned over at a right angle to provide a forwardly directed finger 57, lever 52 being provided, 60 at its outer end, with a similar finger 58. Normally, the fingers 57 and 58 are positioned adjacent partitions 12 and 13 so as not to interfere with the inward movement of the doors 22 and 23. When an article, 65 such as a bottle of milk, is placed upon the platform 45 so as to depress the same, the arms 50 and 52 of the levers will be rocked toward each other so as to occupy a substantially vertical position, bringing the fingers 57 and 58 in close contact with the inner faces of doors 22 and 23 at the center of the compartment. When the levers are moved into this position, the fingers 57 and 58 will be in vertical alignment with pivot 70 pin 51, the upper arms of the levers being on dead center. This positively prevents inward movement of the doors thus serving to lock the compartment and prevent removal of the article, which can only be removed by opening outer cover 6 and the supplemental cover 31. This operation will be clear from Fig. 2 of the drawings, in which the position occupied by the upper arms of bell crank levers 50 and 52, when 75 in locking position, is indicated by broken lines. The operation for the other two compartments will be the same as that just described, and it is not thought necessary to describe the same in detail. 80

85 By this construction, when an article is placed in either one of the compartments, 9, 10 or 11, this article acts to move the locking mechanism into operative position thus automatically closing or locking the particular compartment. It will be evident that there may be slight changes made in the construction and arrangement of the various parts of my invention without departing from the field and scope of the same, 90 and I intend to include all such variations, as fall within the scope of the appended claim, in this application in which a preferred form only of my invention is disclosed. 95

What I claim is:—

In a safe of the character described, a casing having a compartment for receiving articles placed therein, inwardly opening doors hingedly secured to said casing for normally closing the upper end of the compartment, a tripping platform rockably mounted adjacent the lower end of the compartment, means for normally holding said platform in raised position, two oppositely movable bell crank levers rockably mounted in said compartment on the back wall of said casing for movement about a common axis, the upper arms of said levers being of such length as to prevent inward movement

of the doors when the levers have been moved into their extreme position toward each other, connections between the platform and said levers for moving the levers toward each other into operative position 20 when the platform is depressed by an article placed thereon, and a cover for normally closing the front of said casing hingedly secured thereto.

In testimony whereof I affix my signature 25 in presence of two witnesses.

TURE E. NORDBERG.
